[57] **CLAIM**

The ornamental design for a portable sealed environment snack dispenser, as shown and described.

DESCRIPTION

FIG. 1 is a perspective view of a portable sealed environment snack dispenser showing my new design therefor. The broken line drawings representing snacks in the jars and lettering depicting the word "kyles" in any views in which they appear are for purposes of illustration only and form no part of my design; FIG. 2 is a right side elevational view; FIG. 3 is a front elevational view; FIG. 4 is a left side elevational view; FIG. 5 is a top plan view; FIG. 6 is a rear elevational view; and, FIG. 7 is a bottom plan view.

FIG. 1

FIG. 4

FIG. 3

FIG. 2

FIG. 5

FIG. 6

FIG. 7
